UNITED STATES PATENT OFFICE.

ADELBERT F. MOWRY, OF WORCESTER, MASSACHUSETTS.

SPRINKLER HEAD.

1,415,677.

Specification of Letters Patent.

Patented May 9, 1922.

Application filed August 11, 1919. Serial No. 316,577.

To all whom it may concern:

Be it known that I, ADELBERT F. MOWRY, a citizen of the United States, residing at Worcester, in the county of Worcester and State of Massachusetts, have invented certain new and useful Improvements in Sprinkler Heads; and I do hereby declare the following to be a full, clear, and exact description of the invention, such as will enable others skilled in the art to which it appertains to make and use the same.

This invention relates to automatic sprinkler heads. The object of the invention is to reorganize and improve the construction of automatic sprinkler heads to the end that the operation thereof may be rendered more efficient and competent. With this object in view the invention consists in the automatic sprinkler head hereinafter described and particularly defined in the claims. In the drawing illustrating the preferred embodiment of the invention Figure 1 represents an elevation of the improved automatic sprinkler head showing in section the improved fusible joint; Fig. 2 is a perspective of the strut contrivance or retaining device; and Fig. 3 is a section on the line 3—3 of Fig. 1.

The automatic sprinkler head, illustrated in the drawing, is described as follows: The nozzle 10 is provided with a cap or closure 11 constituting the ordinary cap thereof and with the frame 12 rising therefrom and forming part thereof. The improved heat responsive strut contrivance or retaining device is interposed between the frame 12 and cap 11 and comprises a V-shaped member or two-armed bell crank lever 14 and a link member 15. The members 14 and 15 are arranged as illustrated in Fig. 1 in which one arm 16 of the V-shaped member 14 serves as a strut or compression member to hold one end of the link member 15 against an abutment-screw 20 in the frame 12. The end of the screw seats in a depression 21 in the top surface of one end of the link member 15. The link member 15 is provided with a hook 24 at its outer end adapted to slip over and engage the second or flexural arm 17 of the V-shaped member 14. The link member 15 comprises two separate portions 25 and 26 which are provided with tapered holes 30, 31 arranged to be opposite each other when the two members 25, 26 are placed in their operative position. The portion 25 is provided on each side with an

enlarged portion or flange 27 (see Fig. 2) to afford a large fusible material contact area. The fusible joint or connection is provided by filling the opposing tapered holes 30, 31 with fusible material so as to form a fusible rivet 32, and by extending the fusible material over the end of the portion 26 out onto the flanges 27. A shoulder 33 is extended from the surface of the member 25 and serves to assist in positioning the members 25, 26 so as to bring the tapered holes 30, 31 into alignment when the holes are to be filled with fusible material.

By reference to Fig. 1, it is seen that the compression arm 16 of the V-shaped member 14 is offset from the axial line passing through the center of the cap 11 from the center of the screw 20 so that water pressure exerted upon the cap 11 operates through the arm 16 to tend to rotate the link member 15 about the point of contact of the screw 20 therewith. The tendency of the tension member 15 to rotate in this manner is resisted by the engagement of the hook 24 with the end of the arm 17 of the V-shaped member 14. Upon consideration of the forces exerted upon the structure, it is apparent that the individual portions 25, 26 of the link member 15 are subjected to tension as well as flexural stresses tending to pull the member 26 downwardly and to rotate the member 25 upwardly. The structure is rigidly maintained by the fusible rivet 32 and the adhesion of the fusible material to the flange 27 of the member 25.

When the temperature of the room reaches the softening point of the fusible material, the water pressure exerted upon the cap 11 is transmitted to the link member 15 in the above described manner and operates to cause the portion 25 of the member 15 to be moved slightly upwardly, the portion 26 being restrained from movement by the engagement of the hook 24 with the end of the arm 17. The continued movement of the portion 25 operates to shear the fused or softened rivet 32 so that the portions 25 and 26 are immediately expelled in divergent directions thus releasing the water from the nozzle. As the member 25 is rotated upwardly about its point of contact with the screw 20, the member 26 is rotated about the end of the arm 17 so that it is seen that the two individual portions, in addition to being pulled apart so as to shear the rivet, are also moved in divergent directions whereby

the chances of resetting the fusible material are eliminated.

Experience with previous constructions has shown the necessity for the individual elements of the structure to be made substantial enough to withstand the continuous application of considerable water pressure without distortion or yielding in any way. In order to accomplish this result, it will be observed that both the V-shaped member 14 and the individual portions 25, 26 of the link member 15 are of sufficient strength to withstand all degrees of pressure which they are likely to be subjected to. It has also been found in practice that the successful operation of automatic sprinkler heads depends to considerable extent upon the construction and design of the fusible joint. It is recognized that with the lapse of time, the adhesion of fusible material to the surfaces of the members deteriorates so that if reliance is placed solely upon the adhesion, the joint will gradually weaken until finally the device operates to release the water from the nozzle. Also the adhesion of one material to another is sometimes destroyed by sudden shock or jar. The present construction of improved fusible joint aims to prevent all difficulties which have arisen in practice with all other types of joints. The fusible material in the tapered holes 30, 31 forms a double headed rivet so that the joint not only successfully resists the tendency of one member to slide upon another and thus shear the joint, but the opposing tapers also resist any tendency of the members 25, 26 to move away from one another. In order to reinforce the fusible rivet a considerable mass of fusible material envelops the head 40 of the rivet and is secured by adhesion to the flanged portions 27.

An important feature of the invention resides in its simplicity and practicability.

While the preferred embodiment of the invention has been illustrated and described, it is to be understood that the same may be embodied in other forms within the scope of the following claims:—

1. An automatic sprinkler head having, in combination, a nozzle having a frame, a cap adapted to close the nozzle, a two-member heat responsive device interposed between the cap and frame consisting of a triangular structure, two legs of the triangular structure being formed by a V-shaped two armed member and the third leg by a single member cooperating with the

ends of the arms of said two armed member, said heat responsive device having provision whereby one leg of the triangular structure is subjected to a direct tensile stress in the direction of its length, and a fusible joint in said leg.

2. An automatic sprinkler head having, in combination, a nozzle having a frame, a cap adapted to close the nozzle, a two-member heat responsive device interposed between the cap and frame consisting of a triangular structure, one leg of the triangular structure serving as a direct compression strut, the second leg being formed integrally therewith and extended at an angle therefrom and the third leg being formed by a single member cooperating with the ends of the other two legs, said heat responsive device having provision whereby one leg of the triangular structure is subjected to direct tensile stress in the direction of its length, and a fusible joint in said leg.

3. An automatic sprinkler head having, in combination, a nozzle having a frame, a cap adapted to close the nozzle, a two-member heat responsive device interposed between the cap and frame consisting of a triangular shaped structure, two legs of the triangular structure being formed by a V-shaped two armed member and the third leg by a single member, one end of the latter being hooked over the end of one arm of the two armed member, said single member being subjected to tension in the direction of its length, and a fusible joint in said single member.

4. An automatic sprinkler head having, in combination, a nozzle having a frame, a cap adapted to close the nozzle, and a two-member heat responsive device interposed between the cap and the frame consisting of a triangular structure formed by a V-shaped two armed member having arms of substantially equal length, one of which is arranged to serve as a direct compression member, and a lever provided with a fusible joint, one end of said lever being hooked over the end of the second arm of the two armed lever and the other end being interposed between the end of the first arm of the two armed member and the frame, the point of contact of the first arm of the two armed member and said lever being arranged to lie outside of the center line between the cap and the frame.

ADELBERT F. MOWRY.
